SPOOL SPINDLE JOURNAL MOUNTING

George A. Spencer, Akron, Ohio, and Harold R. Sell, Pottstown, Pa., assignors to The Firestone Tire & Rubber Company, Akron, Ohio, a corporation of Ohio

Application April 8, 1954, Serial No. 421,900

5 Claims. (Cl. 242—130)

The invention relates generally to filament spools and devices for level winding filament thereon. More particularly, the invention relates to a filament spool construction having improved mounting means and improved level wind mechanism.

The improved construction of the present invention is adapted for use in a machine having a plurality of spools for continuously winding filament such as extruded plastic under constant tension. A machine of this type is disclosed in the copending application of George A. Spencer and Clarence F. Poetter, Serial No. 421,832, filed April 8, 1954, and entitled Apparatus For Continuously Tensioning And Winding Filaments.

In winding filaments under constant tension on a plurality of spools it is important that each filament be prevented from tangling with other filaments, and from getting in between the rotating parts of the spool spindle and the stationary housing therefor which would interfere with the constant tension applied to the filament. Moreover, it is necessary that the traverse or level wind mechanism for each spool function to level wind the filament on the spool accurately at all times in order to maintain constant tension on the filament as it is wound.

It is an object of the present invention to provide novel mounting means for the spool spindle, and novel traverse mechanism cooperating with said spool, whereby entanglement of the filament is prevented and constant tension on the filament may be accomplished.

Specifically, it is an object to provide an improved spindle and housing construction for the spool which prevents any filament from entering between the stationary and rotating parts thereof.

A further object is to provide an improved traverse mechanism which is easily adjusted in relation to the spool, and which is adapted accurately to level wind the filament on the spool over long periods of use.

These and other objects are attained by the simple and inexpensive constructions comprising the present invention, a preferred embodiment of which is shown by way of example in the accompanying drawing and described in detail herein. Various modifications and changes in details of construction may be made within the scope of the invention defined in the appended claims.

Referring to the drawings:

Fig. 1 is a transverse sectional view through the spool table of a filament winding apparatus showing two spools mounted in side-by-side relation, and the traverse devices for the spools;

Fig. 2 is an enlarged sectional view on line 2—2, Fig. 1, showing the mounting for the spool spindle; and

Fig. 3 is an enlarged sectional view on line 3—3, Fig. 1, showing the construction and mounting of the traverse pulleys.

The spool table preferably includes angular supporting legs 10 and a table top consisting of transverse bars 11 resting on the legs 10 and supporting plates 12 forming the top surface of the table. Two parallel rows of spools arranged longitudinally of the table may be carried on

2

the table top, and one spool of each row is indicated in chain lines at 13A and 13B.

The spindle housings indicated generally at 14A and 14B are substantially identical, except that the cover 15B may have an upper extension 16B for supporting the spool 13B on spindle 17B at a slightly higher level than spool 13A, as shown, although both spools may be at the same elevation if desired. As shown in Fig. 2, the spindle housing 14A has a cap 15A with an upper extension or boss 16A secured to the spindle 17A by a set screw 18, and the cap is supported on an enlarged shoulder 19 on the spindle. Immediately below the shoulder 19 is a bearing portion 20 and spaced below said portion 20 is a similar bearing portion 21.

15 The bearing portions 20 and 21 are journaled in anti-friction ball bearings 22 and 23 respectively, which are mounted in a cylindrical housing member 24 having an annular flange 25 supported on the table top plates 12. The lower bearing 23 abuts a lock washer 26 engaged 20 by a nut 27 threaded on the spindle, and the outer race of bearing 23 is abutted by a bottom cap 28 which is secured to the lower end of housing member 24 by screws 29. The lower end 17A of spindle 17A extends 25 below the bottom cap 28 and is driven by a suitable constant horsepower motor (not shown) adapted for winding filament on the spool 13A at constant tension. Preferably each spindle is driven by an individual constant horsepower motor.

An annular lubrication plate 30 fits around the shoulder 19 of the spindle on top of housing member 24, and has an annular groove 31 containing an oil wick 32 for lubricating the ball bearings below. A lubricant supply tube 33 may be screwed into the side of plate 30 and communicates with the wick 32.

An annular cap plate 35 rests on top of the plate 30 and surrounds the shoulder 19, and the plates 30 and 35 may be secured to the top of housing member 24 by screws 36. As shown in Fig. 2, the outer diameter of cap plate 35 is substantially larger than the outer diameter of plate 30 which is equal to the outer diameter of housing 24, so that the cap plate provides an overhanging annular flange or shoulder around the top of the spindle housing. The top cover 15A has a downturned annular flange 37 which completely surrounds and covers the shoulder of plate 35.

45 Accordingly, when the spindle 17A and cover 15A are rotated to rotate the spool 13A and wind filament thereon, any broken ends or parts of filament which drop below the spool are deflected below cap plate 35 by the flange 50 37 of the cap. Should any filament wrap around the stationary housing 24 and plate 30, any tendency it might have to work upwardly between the housing and the rotating cover is prevented by the overhanging shoulder around the rim of plate 35. If broken filaments were 55 permitted to enter between the stationary and rotating parts of the spindle housing they would soon interfere with the maintenance of constant tension on the filament being wound on spool 13A, which might result in slackness in the filament coming to the traverse mechanism and consequent entanglement with other filaments.

60 Referring to the traverse mechanisms for the spools 13A and 13B, these include pulleys 40 mounted on vertical rods 41A and 41B extending slidably through the table top plates 12. Rod 41B is somewhat longer than rod 41A so that the pulley for spool 13B traverses that spool at its higher elevation. The lower ends of rods 41A and 41B are secured by nuts 42 to the ends of a horizontal connecting bar 43 below the plates 12, and the bar is secured to the top of a beam 44 which extends longitudinally of the table and supports similar bars one 65 for each pair of spools. The beam may be moved up and down by a hydraulic cylinder or the like to cause

the pulleys 40 to traverse their spools and level wind filaments thereon, and suitable means are provided to maintain the beam horizontal, such as shown in said co-pending application of Spencer et al., Serial No. 421,832.

Referring to Fig. 3, each pulley 40 is mounted on top of its rod 41A or 41B by means of an adjusting screw 45, which has a knurled head 46 and a shank 47 is threaded into an axial bore 48 in the rod. A lock nut 49 is screwed on the threaded shank 47 and abuts the top of the rod 41A to lock the screw 45 in adjusted position. The bottom of the lock nut is preferably beveled as shown. The pulley 40 is preferably journaled on the screw 45 immediately under the head 46 by means of an anti-friction bearing 50 which is preferably held in place by a snap ring 51.

By loosening the lock nut 49 and turning the head 46 of the screw, the pulley 40 can be adjusted so that it moves up and down with the beam 44 in register with its spool 13A, and the lock nut when screwed into abutment with the top of the rod locks the pulley in adjusted position. Moreover, the pulleys are easily removed and replaced in a similar manner.

Each pulley groove has a substantially rectangular sharp U shape in cross section so that the filament can ride in one corner or the other of the groove. As all of the filaments F normally are brought down to the pulleys 40 from a higher elevation than the tops of the spools, the filaments ride in the upper corners of the pulley grooves as indicated in the drawings. Thus the filament is maintained in an exact position relative to the spool, resulting in accurately level winding the filament on the spool as the pulley moves up and down, in contrast to the relatively inaccurate level winding which would be accomplished by a pulley having a rounded groove allowing movement or slipping of the filament across the groove.

Furthermore, the rectangular groove pulley gives twice the wear of a V groove pulley, because when one corner of the rectangular groove pulley becomes worn, it requires little time and effort to remove the pulley and invert it on the adjusting screw, so that the filament will ride in the opposite corner.

The improved filament spooling construction of the present invention is simple and inexpensive to construct and repair, is adapted to prevent entanglement or other interference with maintaining constant tension on the filament as it is wound, and accomplishes accurate level winding of the filament on the spool over long periods of use.

What is claimed is:

1. Filament spooling construction including a housing, a spool spindle journaled in said housing, a cap plate secured to one end of the housing and forming an annular shoulder projecting radially beyond the exterior of said housing, and a cover secured to the spindle exte-

riorly of said top plate and having an annular flange covering said annular shoulder and terminating flush with the bottom of said shoulder.

2. Filament spooling construction including a vertical housing, a spool spindle journaled in said housing, a cap plate secured to the top of the housing and forming an annular shoulder overhanging the exterior of the housing, and a cover secured to the spindle above the cap plate and having an annular flange covering said annular shoulder and terminating flush with the bottom of said shoulder.

3. Filament spooling construction including a vertical housing, a spool spindle journaled in said housing, a cap plate secured to the top of the housing and forming an annular shoulder overhanging the exterior of the housing, a cover secured directly to the spindle above the cap plate, said cover plate having a downturned annular flange covering said shoulder and terminating flush with the bottom of said shoulder, and an upper extension on said cover for supporting a spool at a fixed height.

4. Filament spooling construction including a vertical housing, a spool spindle journaled in said housing and having an enlarged shoulder, a cap plate secured to the top of the housing and surrounding said shoulder, said cap plate overhanging the exterior of said housing around its periphery, and a cover secured directly to the spindle above the cap plate and abutting said enlarged shoulder, said cover having a downturned annular flange covering the periphery of said cap plate and terminating flush with the bottom surface thereof.

5. Filament spooling construction including a vertical housing, a spool spindle journaled in said housing and having an enlarged shoulder, a cap plate secured to the top of the housing and surrounding said shoulder, said cap plate overhanging the exterior of said housing around its periphery, a cover secured directly to the spindle above the cap plate and abutting said enlarged shoulder, said cover having a downturned annular flange covering the periphery of said cap plate and terminating flush with the bottom surface thereof, and an upper extension on said cover for supporting a spool at a fixed height.
